UNITED STATES PATENT OFFICE

ARTHUR J. BRAUER AND FREDERICK P. WAGNER, OF ST. LOUIS, MISSOURI

DESIGN FOR A SHOE

Application filed December 14, 1931. Serial No. 42,087. Term of patent 7 years.

To all whom it may concern:

Be it known that we, ARTHUR J. BRAUER and FREDERICK P. WAGNER, citizens of the United States, residing at the city of St. Louis, State of Missouri, have invented a new, original, and ornamental Design for Shoe, of which the following is a specification, reference being had to the accompanying drawing, forming part thereof.

Figure 1 is a worm's-eye view of a shoe bottom illustrating our design as applied to a heel of the French type.

Figure 2 is a view in front elevation of the shoe illustrated in Figure 1, with the fore-part thereof broken away to more fully reveal our design for the breast portion of the heel.

In accordance with our design which is illustrated in the accompanying drawing as applied to heels of the French type, an embellishment is placed upon the breast portion of the heel of a shoe. Slender tapering figures are particularly ornamental for the breast portions of relatively high heels especially when the shoe is so proportioned as to expose a substantial area of the heel breast to occasional view.

We claim:

The ornamental design for a shoe substantially as shown and described.

In testimony whereof, we affix our signatures this 24th day of November, 1931.

ARTHUR J. BRAUER.
FREDERICK P. WAGNER.
